UNITED STATES PATENT OFFICE

145,668

DESIGN FOR A CIGARETTE CONTAINER

George L. Kearney, Tuckahoe, N. Y.

Application March 29, 1945, Serial No. 118,769

Term of patent 14 years

(Cl. D85—2)

To all whom it may concern:

Be it known that I, George L. Kearney, a citizen of the United States of America, residing at Colonial Heights, Tuckahoe, in the county of Westchester and State of New York, have invented a new, original, and ornamental Design for Cigarette Containers, of which the following is a specification, reference being had to the accompanying drawing, forming a part thereof, and wherein

Fig. 1 is a front elevational view of a cigarette container, showing my new design,

Fig. 2 is a side elevational view thereof, looking toward the right of Fig. 1, and

Fig. 3 is a top plan view thereof.

I claim:

The ornamental design for a cigarette container, substantially as shown.

GEORGE L. KEARNEY.
